UNITED STATES PATENT OFFICE.

WILLIAM F. OVERBAGH, FRANKLIN OVERBAGH, AND IRVIN H. BRENT, OF CHICAGO, ILLINOIS, ASSIGNORS TO OVERBAGH AND AYRES MANUFACTURING COMPANY, OF CHICAGO, ILLINOIS, A CORPORATION OF ILLINOIS.

ELECTRIC-LIGHT FIXTURE.

1,017,267.

Specification of Letters Patent. Patented Feb. 13, 1912.

Application filed November 3, 1911. Serial No. 658,332.

To all whom it may concern:

Be it known that we, WILLIAM F. OVERBAGH, FRANKLIN OVERBAGH, and IRVIN H. BRENT, citizens of the United States, and residents of Chicago, in the county of Cook and State of Illinois, have invented certain new and useful Improvements in Electric-Light Fixtures; and we do hereby declare that the following is a full, clear, and exact description thereof, reference being had to the accompanying drawings, and to the letters of reference marked thereon, which form a part of this specification.

Our invention relates to improvements in electric light fixtures, and consists of the matters hereinafter described and more particularly pointed out in the appended claim.

In the accompanying drawings illustrating our invention: Figure 1 is a view representing a section through the longitudinal central axis of our improved fixture, showing the lamp socket located therein partly in elevation. Fig. 2 is a view representing a cross-section in a plane indicated by the line 2—2 of Fig. 1. Fig. 3 is a view representing a vertical section in a plane indicated by the line 3—3 of Fig. 2. Fig. 4 is a fragmentary vertical sectional view partly in elevation, similar to the view shown in Fig. 1, showing our improved device as used with a modified form of lamp socket.

Our improved electric light fixture embodies in its preferred form a tubular shell adapted to be attached to a wall bracket or electric wire conduit; a longitudinally adjustable lamp socket located therein, provided with longitudinally spaced annular grooves formed in its outer surface; means carried by the tubular shell adapted to engage within one of the grooves in the socket to lock it in a predetermined position in said shell; and a shade supporting member made rigid with said tubular shell and adapted for the support of a shade.

Referring to that embodiment of our invention illustrated in Figs. 1 to 3, inclusive, of the drawings, 10 indicates a tubular shell of a diameter to receive a lamp socket 12, and 14 an annular band located below said tubular shell and of a larger diameter than said shell with which it is made integral, as shown in the drawings. Said band is adapted to receive and support the top flange of a shade 15 (shown in dotted lines) which

is clamped within it by clamp screws 16 projecting radially through and having screw-threaded engagement with said band. The tubular shell 10 and the annular band 14 are connected together by a flaring annular flange 17. The top 18 of the tubular shell 10 is dome shaped and is provided with an aperture 19 in which is secured an internally screw-threaded thimble or collar 20. Said thimble 20 is adapted to be threaded upon a suitable fitting on a conduit pipe or wall bracket through which the wires 21, 21 connected to the lamp socket 12 are led. The lamp socket 12 is provided on its outer surface with longitudinally spaced annular grooves 22, 22 (as shown in the drawings, two in number) and the tubular shell 10 is provided with apertured nipples 23, 23, 23, all located in the same horizontal plane and arranged at annularly spaced intervals about the said tubular shell, through which nipples are threaded supporting set-screws 24, 24, 24, adapted for engagement with one of the said grooves 22, 22 in the lamp socket. Vertically extending, transverse lugs 25, 25, are provided in the respective grooves 22, 22 to form stops against which the inner end of one of the supporting set-screws 24, 24, 24, is adapted to abut to prevent the lamp socket 12 from rotation when clamped in the tubular shell.

The improved fixture constitutes a combined lamp socket and shade holder which supports each of said devices independently of the other. When the fixture is in use, the lamp shade 15, shown by dotted lines in Fig. 1, is held in the shade supporting member 14 by the clamp screws 16 engaging the same, and all weight of the shade is upon the fixture and not on the lamp socket. The lamp socket 12 with its incandescent bulb is secured within the tubular shell 10 by the supporting set-screws 24, 24, 24, engaging within one of the grooves 22, 22. It is apparent that the position of the lamp socket 12 may be adjusted lengthwise of the tubular shell 10 to correspond with the grooves 22 in its outer surface, as shown by the full and dotted lines in Fig. 1. By reason of this adjustment the bulb secured to the lamp socket may be brought into a proper position with respect to the reflecting surface of the shade. When the set-screws 24, 24, 24, are disengaged from the grooves 22, 22, the lamp

socket 12 can be detached from the shade holder to remove the same, and another socket substituted therefor, without dismantling the fixture.

5 As shown in Figs. 1 to 3, inclusive, the lamp socket 12 is of a well-known type, consisting of two parts, 26, 27, made of porcelain or other insulating material, the upper part 26 having a recess 26^a in its lower end, 10 in which is secured the usual threaded shell contact 28, and the lower part 27 consisting of a ring 29 threaded upon the shell contact 28, and having a radial flange 30 adapted to engage with the lower end 26^b of the 15 upper part 26. In the case of such a lamp socket, in order to provide the grooves for engagement with the supporting set-screws 24, 24, 24, of the shell 10, as above described, we provide a metallic shell 31 adapted to 20 surround the upper part 26 of the lamp socket and secure said shell to the lamp socket by means of an inwardly projecting radial flange 31^a formed at the bottom of said shell 31, and adapted to be clamped between the lower end 26^b of the upper part 26 and the radial flange 31^a of the ring 29. 25 (See Fig. 3). The annular grooves 22 are formed in said shell 31.

When a lamp socket is especially designed 30 for the fixture, we form the longitudinally spaced annular grooves directly in the insulating body of the socket, as shown in Fig. 4. In said figure, 12^a indicates a lamp socket of insulating material having longitudinally spaced annular grooves 22^a, 22^b, 35 formed in its outer surface, and the socket is secured and supported within the tubular

shell 10 by the supporting set-screws 24^a engaging within one of said grooves 22^a, 22^b, as before described. 25^a, 25^b indicate the vertically extending transverse shoulders provided to form stops for the purpose, before described. It is obvious that any number of said longitudinally spaced annular grooves may be formed in the lamp socket and any degree of adjustment of the same within the tubular shell be thus provided for.

40 We claim as our invention:

An electric light fixture comprising a tubular shell, a lamp socket located therein and capable of adjustment lengthwise of said shell, said lamp sockets being provided with longitudinally spaced, annular grooves formed in its outer surface, means for securing said socket at one of a plurality of predetermined longitudinally spaced positions in said shell, said means comprising annularly spaced set screws projecting through the tubular shell and adapted to engage within one of the annular grooves in said socket, and a shade supporting member located below said tubular shell and made integral therewith.

45 In testimony, that we claim the foregoing as our invention we affix our signatures in the presence of two witnesses, this 26th day of October A. D. 1911.
